UNITED STATES PATENT OFFICE.

BEVILL W. WHITWORTH, OF CEDAR FALLS, IOWA, ASSIGNEE TO CHARLES S. WHITWORTH, OF CEDAR FALLS, IOWA.

TOOL FOR SECURING ENDS OF WIRES.

1,151,640.

Specification of Letters Patent. Patented Aug. 31, 1915.

Application filed January 18, 1915. Serial No. 2,943.

To all whom it may concern:

Be it known that I, BEVILL W. WHITWORTH, a citizen of the United States of America, and a resident of Cedar Falls, 5 Blackhawk county, Iowa, have invented certain new and useful Improvements in Tools for Securing Ends of Wires, of which the following is a specification.

My invention relates to improvements in 10 wire-working devices, and the object of my improvement is to supply a tool adapted for securing an end of a wire about itself securely after the wire has been looped or attached to some supporting structure. This 15 object I have accomplished by the means which are hereinafter described and claimed, and which are illustrated in the accompanying drawings, in which:

Figure 1 is a left-hand side elevation of 20 my improved tool. Fig. 2 is a front elevation thereof. Fig. 3 is a right-hand elevation thereof. Fig. 4 is a rear side elevation thereof. Fig. 5 is a top view of the tool, partly in section. Fig. 6 is a fragmentary 25 detail of the upper end only of the handle-part of said tool. Fig. 7 is a left-hand side elevation of the tool in its first operative position in becoming mounted upon a wire secured to a support. Fig. 8 is a front elevation 30 of said tool in its second operative position where completely mounted upon and engaged with the parts of said wire to be acted upon. Fig. 9 is a view of said tool in its final position, upon completion of its 35 office of twisting the wire-end about the main body of the wire.

Similar characters of reference denote corresponding parts throughout the several views.

40 My improved device comprises a flat metallic handle B, having at its upper end a relatively large circular opening 13 in which is rotatably mounted the middle cylindrical part 18 of the double ratchet A of the tool. 45 The handle B has a part cut out of one side at 14 to form an obliquely directed passage into said opening 13, and adapted to register with a relatively deep longitudinal radial groove 2 in said ratchet A, said groove extending a little past its axis in order to receive the wire H axially thereinto.

The body A has the reversed ratchets 1 and 8 engaged respectively by the pawls C and E, said pawls in turn being limited in 55 swinging away from the ratchets by stops

D and F mounted on the handle B. This permits the device to be used as either a right or a left-hand tool. The body A has integral spaced clutch projections 3, 4 and 5 on its left-hand end grouped about its 60 axial opening 7, of which the projections 3 and 4 are separated by the groove 2, while they are both separated by the diametral end-groove 6 from the opposite projection 5. The opposed faces of said projections, or 65 inner walls of the groove 6 are troughed, as indicated in Fig. 5, and the outer ends of said projections 3 and 5 are beveled or gradually diminished in thickness at their upper and lower parts respectively to afford 70 proper clearance for the wire-end 16 while being operated upon. The grooves 2 and 6 are at right angles to each other, with the axial opening 7 at the middle of the groove 6. On the opposite or right-hand end of the 75 body A is an integral projection 9, cylindrical, concentric with the axis of A and cut away from the top and end to provide respectively a groove 12 into which another groove 11 opens to leave a hook-shaped part 80 10, so that the grooves 11 and 12 both extend past the axis of said body.

The device is primarily intended for use in securing a wire end about the main body 85 of the wire after the latter has been looped about or otherwise secured to a supporting structure such as that shown in Figs. 7 to 9.

The troughed body G represents the upper end of a gate-stile, having a transverse orifice (not shown) through which the wire H 90 is passed, the latter then being bent around one side of the stile across one vertical edge, passed under its main horizontal part and then bent upwardly to provide the vertically extending end 16. The wire end 16 is then 95 in position to be operated upon by said tool.

In Fig. 7, the tool is shown as having been turned about to permit the horizontal part of the wire H to be inserted within the groove 12 of the ratchet-body A. The tool, as shown in said Fig. 7, is then turned back to the left to seat said wire in the registering grooves 11 and 7, the tool being pushed to the left to seat the wire-end 16 in the groove 6 against the troughed alined inner faces of the projections 3 and 4. The tool is now in proper position to work upon and twist the end 16 about the wire H, the projections or grabs 3, 4 and 5 coöperating to 100 seize the end 16 and twist it about the main 105 110

wire H, when the handle B is swung upwardly and then used to operate the ratchet 1 by means of the pawl C. This bends the wire end into a desired number of securing 5 coils 17 about the wire H. The wire end may be bent reversely about the wire H when the tool is to be operated to work the other ratchet 8 in a reverse direction. This 10 tool is of inexpensive construction, and its use saves much loss of time in securing the wire end about the main wire.

The device may be employed wherever necessary, by wire-workers, linemen, or others, and slight departures in construction, 15 materials or proportions of the parts will not depart from the principles of or scope of the protection of this invention.

Having described my invention, what I claim as new and desire to secure by Letters 20 Patent, is:

1. A tool for securing ends of wires, comprising a handle, a rotatable body mounted thereon having an axial orifice and circumferential ratchet-teeth, a pawl mounted on 25 said handle and movably engaging said teeth, said body having a longitudinal groove extending from said axial orifice to its exterior, said body having wire-clutching means on one head arranged at an angle 30 to said longitudinal groove, and having on its opposite head a hook-shaped abutment with its hooked part crossing said groove between said axial orifice and the circumference of the body and spaced from the 35 adjacent head of the latter.

2. A tool for securing ends of wires, comprising a handle, a rotatable body mounted thereon having an axial orifice, said body having two sets of integral ratchet-teeth 40 versed with relation to each other, pawls mounted on said handle and movably engaging said sets of ratchet teeth respectively, said body having a longitudinal

groove extending from said axial orifice to its exterior, said body having wire clutching 45 means on one head arranged at an angle to said longitudinal groove, and having on its opposite head an abutment crossing the end-opening of said longitudinal groove in spaced relation from the said body, said 50 abutment being open along one side.

3. A tool for securing ends of wires, comprising an orificed handle having a transverse opening near one end in communication with its orifice, a rotatable body seated 55 in said orifice and provided with two sets of ratchet-teeth, reversed with relation to each other and located on opposite sides of said handle, said body having an axial orifice and a longitudinal groove opening outwardly from said axial orifice to be placed in occasional registration with the transverse opening in said handle when the body is rotated, pawls mounted on opposite sides of said handle and engaging respectively 60 said reversed sets of ratchet-teeth, wire clutching jaws fixed on one head of said body to provide a groove between with 65 troughed opposed walls, one of the jaws being intersected at a right angle by said longitudinal groove, the jaws having their relatively opposite ends on opposite sides of their interspace gradually diminished in thickness toward the circumference of the body, and said body having on its opposite 70 head a hook-shaped abutment carried across the end opening of said longitudinal groove in spaced relation to the body and between the axial orifice of and the circumference of said body.

Signed at Waterloo, Iowa, this 2nd day of January, 1915.

BEVILL W. WHITWORTH.
